(57) **CLAIM**

The ornamental design for a weightlifting bed, as shown and described.

DESCRIPTION

FIG. 1 is a perspective view of a weightlifting bed showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view of the weightlifting bed in an alternate configuration.

The broken lines depict portions of the weightlifting bed and form no part of the claimed design.

1 Claim, 8 Drawing Sheets
